SOLVENT REFINING OF LUBRICATING OIL

Richard J. Dearborn, Summit, and William P. Gee, Plainfield, N. J., assignors to The Texas Company, New York, N. Y., a corporation of Delaware

Application May 10, 1934, Serial No. 724,840

1 Claim. (Cl. 196—17)

This invention relates to refining mineral oil with solvents for the production of lubricating oil.

The invention contemplates a process of refining mineral oil containing so-called naphthenic and paraffinic, including wax, constituents where-in the oil is extracted to remove the naphthenic constituents and thereafter dewaxed with a suitable selective solvent liquid or liquids in the presence of the same diluent or modifying solvent liquid.

More specifically, the invention contemplates diluting the oil with a solvent liquid of the character of benzol, one of its homologs, a mixture 15 of benzol or its homologs, or a low-boiling petroleum fraction of the character of propane and butane. This dilute mixture is then extracted with an extraction solvent comprising furfural whereby the mixture is separated into a paraffinic 20 phase and a naphthenic phase. The paraffinic phase or raffinate portion comprises the paraffinic constituents including wax mixed with the bulk of the diluent solvent liquid and some furfural, while the naphthenic phase or extract portion 25 comprises the naphthenic constituents of the oil dissolved in furfural and some of the diluent solvent liquid.

The raffinate mixture, after separation of the extract, and without stripping any of the diluent 30 from the raffinate, is subjected to cooling for the purpose of separating all or a portion of the furfural contained therein and which is thus recovered for reuse in the extracting step.

The remaining mixture comprises mainly wax- 35 bearing oil and a large proportion of the original diluent solvent. A wax anti-solvent liquid of the character of acetone and methyl ethyl ketone may be mixed therewith so as to provide a solvent mixture which is selective between wax and 40 oil at temperatures of the order of 0° F. and below. If necessary, additional diluent solvent may be added. This mixture is then chilled in order to solidify the wax, which solidified wax may be removed by settling, centrifuging, or filtration.

An important advantage of the process resides 45 in the employment of a suitable diluent solvent liquid which is adapted to be used in both the extraction and the dewaxing steps, and thereby avoiding any necessity for stripping the diluent 50 prior to dewaxing. The use of a diluent during the extraction step is of particular advantage in that a more effective contact between extraction solvent and oil is realized when the oil is in a dilute state. The separation of the mixture into 55 naphthenic and paraffinic layers is also more

readily facilitated in the case of a dilute mixture.

It is, therefore, an object of the invention to employ, as the diluent in the extraction step, one which will also provide, when mixed with a suitable wax anti-solvent liquid, a satisfactory selective dewaxing solvent mixture. 5

In order to more clearly describe the invention, reference will now be made to the accompanying drawing forming a part of this specification. The oil to be refined which, for example, may be a 10 residual wax-bearing cylinder stock fraction, derived from Mid-Continent crude, is conducted from a tank 1 to a mixer 2 wherein it is mixed with benzol from tank 3. The proportions used may comprise about three parts of benzol to four 15 parts of oil, although it is to be understood that, depending upon the nature of the oil undergoing treatment, these proportions may be reversed, so that the proportion of benzol to oil used may be considerably greater. For example, it may be 20 desirable to employ four or five parts of diluent to one part of oil.

The mixing may be carried out at temperatures of around 100° to 150° F. although lower temperatures may be employed. This mixture is 25 then conducted to the lower portion of an extracting chamber 4 through which it flows upwardly and countercurrently to a body of furfural.

The furfural is conducted from a tank 5 to 30 the upper portion of the chamber 4. The furfural is advantageously introduced to the extracting chamber at a temperature of around 225° F. It may, therefore, be necessary to warm 35 the furfural by passage through a heater 6 prior to introduction to the extracting chamber. In some instances, it may be desirable to cool the furfural, particularly where the furfural has been stripped from previously extracted oil and is 40 still hot. In that case, instead of passing the furfural through the heater 6, it may be cooled by passage through a cooler 7 prior to introduction to the extracting chamber.

The temperature at which the extraction solvent is introduced to the extraction chamber 45 will, of course, depend upon the particular temperature conditions which it is desired to maintain within the chamber. Usually, it may be desirable to maintain a temperature of around 180° F. at the top of the chamber, with a temperature 50 of about 150° F. at the bottom. If it is desired to maintain different, or reverse, temperature conditions, then the furfural may be introduced at a correspondingly different temperature, ranging, for example, from 150° to 300° F. The ratio of 55

furfural to dilute oil may comprise about two parts of furfural to one part of dilute oil.

The furfural coming into contact with the dilute oil within the extracting chamber 4 dissolves 5 the naphthenic constituents, forming an extract portion, which is withdrawn from the bottom of the chamber through an outlet 8 to a tank 9.

The paraffinic constituents, together with the bulk of the diluent solvent and a relatively small 10 proportion of the furfural, are removed from the top of the extracting chamber through a pipe 10 to a cooling coil 11. This mixture may be cooled to a temperature of around 90° F. or lower, whereupon a substantial proportion of the furfural 15 separates from the mixture due to its insolubility therein at low temperatures.

The cooled mixture is introduced to a settler 12 wherein the furfural is separated, withdrawn through a pipe 13, and conducted to the solvent 20 tank 5 for further use.

The remaining mixture, comprising mainly wax-bearing oil and benzol, in the proportions roughly of about two parts or more of benzol to three parts of oil, is conducted from the settler 12 25 to a mixing coil 14, wherein it is mixed with acetone or other suitable wax anti-solvent liquid from a tank 15.

Additional quantities of diluent solvent may be added where necessary from tank 3 through a 30 pipe 16. In this way, a suitable dewaxing mixture, containing around 35% of acetone and 65% benzol, in the proportion of around three parts of acetone-benzol mixture to oil is formed.

This mixture is then conducted through a 35 chiller 17 wherein it is chilled to a temperature of around —10° F. in order to solidify the wax. The cold mixture, containing suspended wax, is conducted through a pipe 18 to a filter 19 wherein the wax is removed as a filter cake to produce a 40 dewaxed filtrate. The wax is accumulated in the tank 20 while the dewaxed filtrate accumulates in tank 21. The solvents may be recovered from the wax and filtrate by distillation or stripping with steam or any other suitable method and thus 45 recovered for reuse.

If desired, the filtration may be carried out in the presence of a suitable filter-aid material such as diatomaceous earth, fuller's earth and the like. In that case, the chilled mixture is conducted 50 from the chiller 17 directly to a mixture 22 wherein it is mixed with filter-aid material contained in the vessel 23. The resulting mixture, containing solid wax and filter-aid material, is then charged into the filter 19.

55 While benzol has been described as the diluent

solvent in the foregoing example, it is contemplated that other diluent solvents, such as propane or butane, may be used. Where normally gaseous material, such as propane, is used, it will be necessary to employ a closed system capable of withstanding sufficient pressure in order to maintain the diluent in a liquid condition. 5

Also, while the extraction step has been described as a continuous countercurrent operation, it is contemplated that intermittent extraction of 10 the batch type may also be employed.

The invention is not restricted to the particular operating conditions described in the foregoing example since the temperatures therein set forth, as well as the proportion of solvents used, may be 15 varied, depending upon the nature of the oil undergoing treatment.

Furthermore, the invention is not limited to the treatment of residual cylinder stock fractions but is applicable to either distillate or residual oils, 20 whether viscous or relatively non-viscous, and irrespective of the source of the oil.

Obviously, many modifications and variations of the invention, as hereinbefore set forth, may be made without departing from the spirit and 25 scope thereof, and therefore only such limitations should be imposed as are indicated in the appended claim.

We claim:

In the manufacture of lubricating oil of low 30 pour test and high viscosity index from viscous wax-bearing mineral oil, the method which comprises diluting wax-bearing oil comprising constituents of cylinder stock viscosity, extracting the dilute mixture with furfural at a temperature 35 of around 150° to 300° F. and substantially above the solid point of the wax constituents, forming an extract phase containing low viscosity index constituents and a raffinate phase comprising high viscosity index oil, wax, some furfural and diluent 40 liquid, cooling the raffinate phase to a temperature of around 90° F. to separate furfural therefrom, removing the portion of furfural so separated, mixing the remaining mixture of raffinate oil, wax and solvent with a further quantity of 45 diluent and aliphatic ketone, such as acetone and methyl ethyl ketone, in proportions such that the solvent mixture has selective action as between oil and wax at a temperature of around 0° F., chilling the mixture to a temperature of 0° F. 50 below to precipitate the wax, and removing the wax so precipitated.
